UNITED STATES PATENT OFFICE.

JOHN S. TRIMBLE, OF SHELBY, OHIO.

SULKY-PLOW.

SPECIFICATION forming part of Letters Patent No. 309,748, dated December 23, 1884.

Application filed February 20, 1884. (No model.)

To all whom it may concern:

Be it known that I, JOHN S. TRIMBLE, of 5
Shelby, in the county of Richland and State
of Ohio, have invented certain new and use-
ful Improvements in Sulky-Plows; and I do
hereby declare the following to be a full, clear,
and exact description of the invention, such as
will enable others skilled in the art to which
it pertains to make and use the same.

10 My invention relates to sulky-plows, the ob-
ject being to provide a land-wheel with adjust-
able and removable cutter-blades arranged cir-
cumferentially and projecting from the per-
iphery of the wheel midway in cross-section,
forming a colter.

15 The invention further consists in the pecu-
liar construction of this wheel, adapting it to
receive and clamp and hold the cutter-blades
in the position required, in a manner herein-
after shown.

20 The invention further consists in securing
the axle for this wheel in such a manner and
providing such actuating mechanism that the
axle may be turned more or less in a horizon-
tal plane, whereby the colter-wheel is made
25 to follow curves and turn corners with ease
and without side draft.

20 The invention further consists in an im-
proved jointer secured by a ball-and-socket
30 joint and otherwise made adjustable.

The invention further consists in the de-
tails of construction and combination of parts
hereinafter described, and pointed out in the
claims.

35 In the accompanying drawings, Figure 1 is
a side elevation of my improved plow, but
with portions of the frame broken away. Fig.
2 is a plan view of the frame, the plow-beam,
wheels, and axles, and a portion of the draft-
40 pole. Fig. 3 is an enlarged side elevation of
a portion of the colter-wheel. Fig. 4 is an ele-
vation of the hub and a portion of the spokes
of the colter-wheel, and in cross-section the
rim of the wheel and the colter-blade. Fig. 5
45 is a view in perspective of two of the colter-
blades, showing the manner of joining them
at the ends. Fig. 6 is an enlarged view in
perspective of the jointer and the ball-and-
socket joint and other adjusting mechanism
50 by which the jointer is held.

The frame of the plow, as shown in Fig. 2,

is constructed of tubing, the pieces of which
are joined together by ordinary "fittings"—
such as elbows, T's, and crosses. When other
portions are to be secured to the frame, T's are 55
used with their side openings of suitable size
and turned in the direction required for secur-
ing such parts.

A and A' are the ends of the frame, to which
are joined the longitudinal parts a, a', a'', and a'''.

A'' is an extension for rigidly supporting the
tongue C'.

B is the plow secured to the beam C, that,
directly over the center of the plow at b, is
pivotally secured to and operates between the 65
parts a' and a''. At the front end the beam
has a limited vertical movement between the
guides c and c', that are secured, respectively,
to the parts a' and a''.

D is a lever of the bell-crank variety, piv- 70
oted at d to the part a'', and the short arm
thereof provided with a laterally-projecting
pin, d', that operates in a slot in the beam C,
as shown in dotted lines in Fig. 1. The long
arm of the lever is provided with a bell-crank 75
lever that operates a spring-dog that engages
notches on the sector D', that is also secured
to the part a''. The spring-dog and attach-
ment are on the back side of the lever and
not shown; but are of the same construction as 80
those shown on lever H'.

By operating the lever D the plow is guided
so as to enter the ground the required depth;
or the point of the plow may be elevated, so
as to pass over obstructions.

85 The wheel E is mounted on the axle E', that
is secured to the parts a and a', preferably by
bolts through the axle, and screwed into the
vertical "side openings" in the T's e and e',
that are above the axle.

90 F is a combined land and colter wheel
mounted on the axle G, that is pivoted by a
bolt (not shown) that passes vertically through
the axle and is screwed into the side opening
of the T g. The inner end of the axle G oper- 95
ates horizontally between the ways H, de-
pending from the part a'', and is slotted to re-
ceive the lower end of the lever H', that is
pivoted at h to the part a''.

99 By means of the lever H' the axle G may be
turned to a limited extent on a horizontal
plane, so as to guide the wheel F, as may be

required, to avoid a side draft in "making curves" or in "turning corners."

To the lever H' is pivotally attached the lever P of the bell-crank variety, the short arm of which is connected by the link p to the spring-dog O , that engages notches on the sector h^2 , and by means of which the lever may be adjusted and held in the position required. The rim of the wheel F is divided circumferentially into two parts, between which are secured the cutter-blades I , that form the colter. The spokes of the wheel are preferably small tubes, and alternate spokes support opposite sides of the rim and are sufficiently flexible to admit of drawing the two parts of the rim toward each other by bolts in securing the cutter-blades. These blades are provided with slots i , through which the bolts j pass. By means of these slots the blades I may be adjusted, so as to extend the distance beyond the periphery of the wheel that is required to sever the turf. The ends of the blades may be made male and female, as shown in Fig. 5, for mutual lateral support. When the bolts j are screwed up tight, the blades I are held firm, as in a vise. By loosening the bolts the blades may be adjusted at any time, and by withdrawing the bolts the blades may be taken out and sharpened by an ordinary blacksmith. These blades are of thin tempered steel, and are therefore durable, and are operated with little power. The wheel F is located at such a distance from the plow on the landside that the colter will sever the turf the width of a furrow from the plow.

In plowing it is desirable that the furrow be turned over and laid down smoothly in the trench of the adjacent previously-turned furrow; but, instead of this, the furrows, when turned down, are inclined to overlap the adjacent furrows. To remedy this difficulty, jointers are provided to slice off the top edge of the furrow when in nearly a vertical position, so that the severed part will first fall into the trench, carrying with it any straw or "litter" that may be on the furrow, after which the remainder of the furrow, as it is turned over, fits snugly down in the trench, so that the plowed field presents that smooth even surface that is the delight of practical farmers.

My improved jointer consists of the blade K , provided with the shank k , that may be bent at any angle required, and that terminates in

the ball k' , that fits in the socket l of the supporting-arm L . This arm is bent at right angles, and the upright part provided with the slot L' , through which the bolt passes that secures the arm to the plow, and by means of which the arm is vertically adjustable. A slot, l' , and a bolt, l'' , is provided. By means of the former the sides of the socket may be separated slightly to admit the ball k' , and by means of the latter the sides of the socket may be drawn together, so as to grasp and secure the ball in the position in which it may be placed in adjusting the blade K . With this construction the jointer is easily and universally adjustable.

M is the seat, supported by one or more springs, m , secured to the frame in any convenient manner. A draft-arm, c^2 , may be attached to the under side of the plow-beam.

In place of the tongue C' , thills may be substituted when required.

What I claim is—

1. In a wheel-plow, the combination, with a frame, a short axle pivoted near its outer end to said frame, and a land-wheel journaled to said axle and provided on its periphery with adjustable cutters, of a lever for moving the axle horizontally, substantially as set forth.

2. In a wheel-plow, the combination, with a frame, a short axle pivoted near its outer end to the frame and supported at its inner end between guides, a wheel, and cutters adjustably secured to said wheel, of a lever for moving the axle horizontally, substantially as set forth.

3. In a sulky-plow, the combination, with the adjustable arm L , provided with an adjustable socket, l , of the jointer K , provided with the ball k' , adapted to operate in said socket, by means of which the jointer is made universally adjustable.

4. In a wheel-plow, the combination, with a frame, a short axle pivoted near its outer end to the frame and supported at its inner end between guides, a wheel journaled on the axle, and cutters secured to the periphery of the wheel, of a lever for moving the axle horizontally, substantially as set forth.

In testimony whereof I sign this specification, in the presence of two witnesses, this 21st day of January, 1884.

JOHN S. TRIMBLE.
